UNITED STATES PATENT OFFICE.

WILLIAM HUGHES BUTTERFIELD, OF STECHFORD, BIRMINGHAM, ENGLAND.

DESIGN FOR A MAGNETO-BRACKET.

50,388.

Specification for Design.

Patented Feb. 20, 1917.

Application filed August 24, 1914. Serial No. 858,372. Term of patent 14 years.

To all whom it may concern:

Be it known that I, WILLIAM HUGHES BUTTERFIELD, subject of the King of Great Britain, residing at Levis Motor Works, Station Road, Stechford, Birmingham, in the county of Warwick, England, have invented a new, original, and ornamental Design for Magneto-Brackets, of which the following is a specification, reference being had to the accompanying drawing, forming part thereof.

The figure is a perspective view of a magneto bracket showing my new design.

I claim:

The ornamental design for a magneto bracket, as shown.

WILLIAM HUGHES BUTTERFIELD.

Witnesses:

WILLIAM E. JONES,
ELSIE M. WILSON.
